poration of America, a corporation of Delaware

Application August 25, 1942, Serial No. 456,012

17 Claims. (Cl. 250—27)

1

This invention relates generally to electronic computers and particularly to a cathode ray tube circuit for counting voltage pulses wherein the cathode ray traverses a target electrode of the cathode ray tube in accurately defined discrete steps.

Heretofore various devices have been disclosed in the field of electronic computers which utilized the deflection of a cathode ray in response to voltages or pulses representative of the quantities under computation. Due to the non-linearity of the deflecting elements of standard cathode ray tubes, various devices and circuits have been utilized to compensate for errors introduced by these factors. For example, compensation for non-linearity in the deflection of a cathode ray tube is disclosed in the United States Patent No. 2,415,190, granted to Jan A. Rajchman on February 4, 1947, wherein the actual deflection of the cathode ray provides a predetermined function of the variable quantities applied to the device as variable deflecting voltages.

The instant invention comprises a pulse counting device which utilizes a cathode ray tube having specially designed target electrodes, in combination with vacuum tube circuits for stepping the cathode ray beam along a predetermined path on a target electrode, in response to applied pulses which are representative of the quantities to be counted. Briefly, the device comprises a cathode ray tube having conventional cathode, control electrode, and anode electrodes. Deflection of the cathode ray is provided by either electrostatic or electromagnetic deflection elements of conventional design. The cathode ray beam is focussed upon a first shield electrode, which includes a series of apertures in the path of the cathode ray beam. Behind, and screened by, the first shield electrode, are two target electrodes. One target electrode extends along the greater portion of the cathode ray path, while the second target electrode is intended for returning the cathode ray beam to its initial position upon the completion of each full scanning operation. The associated thermionic tube circuits provide control voltages for actuating the deflecting elements in response to secondary electronic emission from the two target electrodes. Circuit constants are selected to step the electron beam across the apertured electrode from aperture to aperture in response to the applied pulses. Non-linearity of the deflecting elements is compensated for by the associated circuits to maintain the cathode ray beam within the boundaries of each aperture after the

2

application of the applied pulses, whereby the deflection is accomplished in discrete steps.

Among the objects of the invention are to provide a new and improved method of and means for counting voltage pulses. Another object is to provide a new and improved method of and means for counting voltage pulses, which includes a cathode ray tube and associated circuits in which the cathode ray is deflected in discrete steps across an apertured shield electrode in response to the applied pulses. Another object is to provide a new and improved method of and means for compensating for non-linearity in the deflecting elements of a cathode ray tube, wherein the cathode ray is deflected to a predetermined aperture in a screen electrode, and is maintained within the boundaries of said aperture until a succeeding pulse is applied to the device. Still another object is to provide an improved method of and means for returning the cathode ray beam to an initial position after each complete scanning operation of the target electrode.

The invention will be described in detail by reference to the accompanying drawing of which the single figure is a schematic circuit diagram of a preferred embodiment of the device.

Referring to the drawing, a cathode ray tube 11 includes a cathode 12, a control electrode 13, a screen electrode 14, and an anode 15 which are supplied with operating voltages from the voltage divider 16. A source of high voltage is connected across the voltage divider 16. A resistor 17 is connected between the control electrode 13 and the negative terminal of the voltage divider 16. The tube 11 includes deflecting elements 18, 18' which are located between the anode 15 and an apertured screen electrode 19. A relatively long target electrode 20, and a relatively short second target electrode 21 are disposed behind the apertured target electrode 19. The apertures in the shield electrode 19 are disposed in the deflection path of the cathode ray beam. The apertured screen 19 is maintained at a positive potential by means of the battery 22. The long target electrode 20 is connected to the input of a D.-C. amplifier which includes the first and second thermionic tubes 24 and 25. The output of the second thermionic amplifier tube 25 is applied to charge a capacitor 32, which is connected through a series resistor 33 to the deflecting element 18. The source of input pulses applied to the terminals 23 is likewise connected across the series resistor 33, whereby the input pulses add or subtract from the deflecting voltages normally applied to the 55 deflecting elements 18, 18'.

The second target electrode 21 is connected to the input circuit of a second amplifier which includes the third and fourth thermionic tubes 26 and 27. The output of the fourth thermionic tube 27 is applied to key the input of a pulse lengthening circuit, for example, a multivibrator which includes the fifth and sixth tubes 28 and 29. The output of the last multivibrator tube 29 is connected to the movable element of a switch 30, and to the pulse input circuit of the next succeeding counter circuit. One contact of the switch 30 is connected through a capacitor 31 to the control electrode of the cathode ray tube. A second contact of the switch 30 is connected to the cathode ray deflection electrode 18'. A third switch contact is connected to the anode of tube 24. This impulse may also be applied to the next counter tube, or the next counter row in the same tube.

In operation, pulses applied to the input terminals 23 provide deflection of the cathode ray until it reaches an aperture 1 in the shield electrode 19. Electrons penetrating the shield 19 provide secondary electron emission from the long target electrode 20, thereby raising the potential upon the control electrode of the first thermionic tube 24. This potential is further amplified in the second thermionic tube 25 and applied to the deflecting elements 18 and 18' to maintain the cathode ray within the confines of the aperture 1.

When a second pulse is applied to the input terminals 23 the control potential derived from the target electrode 20 is temporarily overcome, and the ray is deflected until it reaches the second aperture 2 in the screen electrode 19. Penetration of the second aperture 2 by the cathode ray again provides secondary electronic emission from the target electrode 20, which in turn again locks the cathode ray within the confines of the second aperture 2. Any number and arrangement of apertures may be utilized, depending upon the numerical scale and function thereof desired. Succeeding pulses applied to the input terminals 23 connected across the series resistor 33, increase or decrease the deflecting voltages applied to the deflecting elements 18, 18' (depending upon the polarity of the applied pulses), and cause the cathode ray to step across the target electrode 19, until the cathode ray reaches the last aperture A. The cathode ray may be stepped in either direction depending on the polarity of the applied pulses. The applied pulses should be of relatively short duration with respect to the time constant of the deflection control circuit including the amplifier tubes 24, 25. The second target electrode 21 is disposed behind the last aperture A. When the cathode ray beam penetrates the aperture A, secondary electronic emission from the second target electrode 21 raises the potential upon the control electrode of the third amplifier tube 26. This potential is further amplified by the fourth amplifier tube 27 and applied to key the multivibrator comprising the tubes 28 and 29. The output of the multivibrator is applied to the switch 30, which selectively applies the output voltage to the control electrode 13, the deflection element 18' of the cathode ray tube 11, or the anode of the amplifier tube 24. When the multivibrator output voltage is thus applied to the control electrode 13 of the cathode ray tube, the cathode ray beam is temporarily interrupted. The interruption of the beam also interrupts the secondary emission from the second collector electrode 21 and the long target electrode 20, whereby the control voltages derived therefrom are also temporarily interrupted. When the con-

trol potential is removed from the control electrode of the first amplifier tube 24, the cathode ray beam will be deflected to its initial position on the screen electrode 19, due to the absence of holding potentials.

The control potential derived from the last multivibrator tube 29 may, if desired, be applied directly to the anode of tube 24 whereby the multivibrator control potential overcomes the normal control potentials derived from the target electrodes 20 and 21 and returns the cathode ray beam to its initial position. It should be understood that in either case the time constant of the multivibrator output circuit should be sufficient to permit the return of the cathode ray beam to its initial position. This time constant may be determined by selecting the circuit components in a manner well known in the art. If the amplification provided by the tube 25 is not desired, the multivibrator impulse may be applied directly to the cathode ray tube deflecting element 18'.

Thus the invention described comprises a cathode ray tube having an apertured shield electrode and a plurality of target electrodes, with circuits connected to the target electrodes for deriving potentials for controlling the deflection of the cathode ray in discrete steps within predetermined regions of the target electrode.

We claim as our invention:

1. A cathode ray tube circuit for counting voltage pulses including a cathode ray tube having ray generating means, ray deflecting means, at least one target electrode having a secondary electron emissive surface, and an apertured electrode positioned between said deflecting means and said target electrodes for screening said target electrodes, means for applying said pulses to said ray deflecting means to deflect said beam across said target electrodes, and means responsive to said secondary emission for accurately positioning said beam on said target electrode after each application of said pulses to said deflecting means.

2. A cathode ray tube circuit for counting voltage pulses including a cathode ray tube having ray generating means, ray deflecting means, at least one target electrode, and an apertured electrode positioned between said deflecting means and said target electrodes for screening said target electrodes, means for applying said pulses to said ray deflecting means to deflect said beam across said target electrodes and means including said target electrode for accurately positioning said beam in one of said apertures in said apertured electrode after each application of said pulses to said deflecting means.

3. Apparatus of the type described in claim 1 including means for stepping said beam across said target electrode in response to said application of said pulses to said deflecting means.

4. Apparatus of the type described in claim 2 including means for stepping said beam across said target electrode in response to said application of said pulses to said deflecting means.

5. A cathode ray tube circuit for counting voltage pulses including a cathode ray tube having ray generating means, ray deflecting means, a first target electrode, a second target electrode, and an apertured electrode positioned between said deflecting means and said first and second target electrodes for screening said target electrodes, means for applying said pulses to said ray deflecting means to deflect said beam across said target electrodes, and means including said target electrodes for accurately positioning said beam

in one of said apertures in said apertured electrode after each application of said pulses to said deflecting means.

6. Apparatus of the type described in claim 5 including means for stepping said beam across said target electrodes in response to said application of said pulses to said deflecting means.

7. Apparatus of the type described in claim 5 including means including said second target electrode for positioning said ray on a predetermined region of said first target electrode after application of said ray to said second target electrode.

8. Apparatus of the type described in claim 5 including a pulse lengthening circuit, means including said second target electrode and said circuit for positioning said ray on a predetermined region of said first target electrode after application of said ray to said second target electrode.

9. A cathode ray tube circuit for counting voltage pulses including a cathode ray tube having ray generating means, ray deflecting means, a first target electrode, a second target electrode, and an apertured electrode positioned between said deflecting means and said first and second target electrodes for screening said target electrodes, means for applying said pulses to said ray deflecting means to deflect said beam across said target electrodes, an amplifier, means for applying voltages derived from said first target electrode to said amplifier, and means for applying said amplified voltages to said deflecting means for accurately positioning said beam in one of said apertures in said apertured electrode after each application of said pulses to said deflecting means.

10. A cathode ray tube circuit for counting voltage pulses including a cathode ray tube having ray generating means, ray deflecting means, a first target electrode, a second target electrode, and an apertured electrode positioned between said deflecting means and said first and second target electrodes for screening said target electrodes, means for applying said pulses to said ray deflecting means to deflect said beam across said target electrodes, an amplifier, means for applying voltages derived from said first target electrode to said amplifier, means for applying said amplified voltages to said deflecting means for accurately positioning said beam in one of said apertures in said apertured electrode after each application of said pulses to said deflecting means, a second amplifier, a multivibrator, means for applying voltages derived from said second target electrode to said second amplifier, means for keying said multivibrator by said second amplified voltages, and means including said multivibrator for positioning said ray on a predetermined region of said first target electrode after application of said ray to said second target electrode.

11. A cathode ray tube circuit for counting voltage pulses including a cathode ray tube having ray generating means, ray deflecting means, a first target electrode, a second target electrode, and an apertured electrode positioned between said deflecting means and said first and second target electrodes for screening said target electrodes, means for applying said pulses to said ray deflecting means to deflect said beam across said target electrodes, an amplifier, means for applying voltages derived from said first target electrode to said amplifier, means for applying said amplified voltages to said deflecting means for accurately positioning said beam in one of said apertures in said apertured electrode after each

application of said pulses to said deflecting means, a second amplifier, a multivibrator, means for applying voltages derived from said second target electrode to said second amplifier, means for keying said multivibrator by said second amplified voltages, and means including said multivibrator for positioning said ray on a predetermined region of said target electrode and for temporarily blanking said ray after application of said ray to said second target electrode.

12. A cathode ray tube circuit for counting voltage pulses including a cathode ray tube having ray generating means, ray deflecting means, a first target electrode, a second target electrode, and an apertured electrode positioned between said deflecting means and said first and second target electrodes for screening said target electrodes, means for applying said pulses to said ray deflecting means to deflect said beam across said target electrodes, an amplifier, means for applying voltages derived from said first target electrode to said amplifier, means for applying said amplified voltages to said deflecting means for accurately positioning said beam in one of said apertures in said apertured electrode after each application of said pulses to said deflecting means, a second amplifier, a multivibrator, means for applying voltages derived from said second target electrode to said second amplifier, means for keying said multivibrator by said second amplified voltages, and means including said multivibrator and said deflecting means for positioning said ray on a predetermined region of said target electrode after application of said ray to said second target electrode.

13. A cathode ray tube circuit for counting voltage pulses including a cathode ray tube having ray generating means, ray deflecting means, a control grid electrode, a first target electrode, a second target electrode, and an apertured electrode positioned between said deflecting means and said first and second target electrodes for screening said target electrodes, means for applying said pulses to said ray deflecting means to deflect said beam across said target electrodes, an amplifier, means for applying voltages derived from said first target electrode to said amplifier, means for applying said amplified voltages to said deflecting means for accurately positioning said beam in one of said apertures in said apertured electrode after each application of said pulses to said deflecting means, a second amplifier, a multivibrator, means for applying voltages derived from said second target electrode to said second amplifier, means for keying said multivibrator by said second amplified voltages, and means including said multivibrator and said control grid electrode for positioning said ray on a predetermined region of said target electrode after application of said ray to said second target electrode.

14. In a cathode ray tube having ray generating means, ray deflecting means, an apertured screen electrode, and a target electrode, the method of deflecting said ray in discrete steps across said target electrode comprising directing said ray on said screen, deflecting said ray along a path corresponding to the positions of said apertures in said screen, producing secondary electronic emission from said target electrode in response to penetration of said apertures by said ray, deriving a control potential proportional to said emission, and applying said control potential to maintain said ray within progressive apertures along the path of said ray.

18. The method according to claim 14 including the step of deriving a second control potential when said ray penetrates predetermined apertures in said screen, and applying said second control potential to effectively neutralize said first control potential.

16. The method according to claim 14 including the step of deriving a second control potential when said ray penetrates predetermined apertures in said screen, and applying said second control potential to effectively neutralize said first control potential and to bias off said beam generating means.

17. The method according to claim 14 including the step of deriving a second control potential when said ray penetrates predetermined apertures in said screen, and applying said second control potential to effectively neutralize said

first control potential and to bias off said beam generating means for a predetermined time interval.
